GAME

Frederick Douglas Williams, Larchmont, N. Y.

Application May 15, 1941, Serial No. 393,503

10 Claims.

(Cl. 273—134)

This invention relates to games and, more particularly, concerns the provision of a game based upon the conflict between democracy and dictatorship.

More specifically, the present invention involves the provision of a game of war involving one or more democratic countries, as one opponent, and one or more dictator countries, as the other opponent. For convenience in reference, the opponents will be referred to as Democracy and as Dictatorship, respectively.

The principles on which the invention is based will more fully appear from the following description and illustrative drawings.

In the drawings:

Fig. 1 is a plan view of a game board utilized in the game of the present invention;

Fig. 2 is a view of a game piece representing the President or ruler of the Democracy;

Fig. 3 is a view of the game pieces representing soldiers of the Democracy;

Fig. 4 is a view of a game piece representing a symbol or principle of Democracy, such as freedom of speech, press, etc., denominated "Appeal to freedom";

Fig. 5 is a view of a game piece designated "Imprisonment for anti-democratic activities";

Fig. 6 is a view of a game piece representing a Dictator;

Fig. 7 is a view of game pieces representing the Dictator's soldiers;

Fig. 8 is a view of a game piece representing subversive activities, such as and denominated "Fifth column activities" of the Dictatorship;

Fig. 9 is a view of a game piece representing "Censorship" imposed by a Dictator;

Fig. 10 is a perspective view of a pair of chance members or dice used by the player taking the side of Democracy;

Figs. 11 and 12 are plan development views of the dice illustrated in Fig. 10;

Fig. 13 is a perspective view of a pair of chance members or dice used by the player taking the side of Dictatorship;

Figs. 14 and 15 are plan development views of the dice illustrated in Fig. 13;

Fig. 16 is a view of a game board for use in a game played by more than two players.

From the above description of the figures of the accompanying drawings, it will be observed that the present invention makes provision for playing a game of war in which there are utilized not only the military forces of the opponents but also other forces or powers inherent in democracies and dictatorships, respectively, but not strictly military. Thus, on the side of Democracy there is the force or power of the "Appeal to freedom" and the force or power of "Imprisonment for anti-democratic activities," the first mentioned force having a certain

attacking power, while the other has defensive power. On the side of dictatorship, there are the attacking power of "Fifth column activities" and the defensive power of "Censorship." Thus in playing the war game of the present invention the players not only make use of the military forces represented by the soldiers and by the President or Dictator, but also make use of the other forces hereinafter referred to for convenience as "Abstract forces." The throw of dice determines the game pieces which the player is required to move, but the player decides where to move said pieces. Accordingly, the game does not depend merely upon the element of chance but involves as well the judgment or skill of the players.

The player representing Democracy is the winner if he has captured either the Dictator or all the soldiers of the Dictatorship, but the player representing Dictatorship, in order to win, must capture not only the President but all the soldiers of the Democracy.

The game board 10 illustrated in Fig. 1 has represented thereon two adjacent countries separated from each other by the boundary line or border 12. Each country is divided into a plurality of sections marked I, II, III, IV, V, VI and VII, and designated respectively as Agriculture, Industry, Mountains, Highway, Forest, Hills and Mountains. It will be observed that certain of the sections border upon or are adjacent to certain other sections of the same country and that certain of the sections of one country border upon a plurality of sections of the opponent's country. Also, it will be noted that certain of the sections in each country border upon a greater number of sections than certain other sections border on other sections. Thus, for example, section I (Agriculture) borders upon or is adjacent to four other sections namely, section II (Industry), section V (Forest), section IV (Highway) and section III (Mountains) of the same country, while section II (Industry) borders only upon two other sections, namely Agriculture (I) and Forest (V), while section IV (Highway) borders upon five sections of the same country and also one section, namely the Highway of the opposing country. The game pieces illustrated in Figs. 2 to 9 can be moved in any direction, but only from one section to an adjacent section, whether said sections be in the same or in opposing countries. Thus, for example, a game piece initially in section I (Agriculture) can move into any one of sections II, III, IV or V, but cannot move from section I into section VI or into section VII, as neither of said last mentioned sections borders upon or is adjacent to section I. Further, by way of example, a game piece in section III can move either into section I or section IV of

the same country or into section VII of the opposing country, but cannot move into section IV of the opposing country as said last mentioned section does not border upon section III of the opposing country, adjacent or bordering sections being only such as have a boundary line of some length and not merely a point between them.

Considering now the game pieces of the two opponents or enemy countries, respectively, the game pieces of Democracy includes a game piece 14 representing the President or ruler of Democracy, and eight pieces 16 representing soldiers of Democracy, the game piece representing the President having an arbitrary value of four, or any other suitable value greater than that of one soldier, and the game piece representing the soldiers each having an arbitrary value of one, while the Dictatorship has ten soldiers 18 each having an arbitrary value of one and the Dictator 20 having an arbitrary value of five, which is greater than the arbitrary value assigned to the President.

The soldiers or ruler of one country can, if present in sufficient force, capture the soldiers or the ruler of the enemy country. In addition, however, to the rulers and soldiers of the opposing countries, each country has other game pieces which cannot capture the game pieces of the opposing country but which have certain important effects on the latter. For example, in the case of Democracy, game piece 22 denominated "Appeal to freedom" neutralizes or renders powerless the soldiers of the Dictatorship when said game piece is in the same section as that occupied by said soldiers, and, on the other hand, the game piece 24 of the Dictatorship, denominated "Fifth column activities," has a similar effect on the soldiers of Democracy, if placed within a section occupied by the latter. The game piece 26 of the Dictatorship, denominated "Censorship," neutralizes the effect of game piece 22, while the game piece 28 of the Democracy neutralizes the game piece 24 of the Dictatorship, when said opposing game pieces are in the same section, respectively. It will be observed that pieces 22 to 28, respectively, do not represent soldiers or other individuals, but represent measures, principles, or ideas. Accordingly these pieces 22 to 28 cannot capture any other piece but, as indicated, they have certain influence upon soldiers of the opposing countries, respectively, but not upon the President or Dictator. Thus, for example, if the player representing Democracy moves game piece 22 "Appeal to freedom" into a section where there are Dictatorship soldiers, the latter lose confidence in their Dictator and stop fighting, i. e., they become powerless and their value is reduced to zero and they cannot be moved so long as they are under the influence of game piece 22. Further, if under these circumstances, Democracy can move one soldier into said section he can capture all of the Dictatorship soldiers thus rendered powerless because said soldier has a value of one which, of course, is greater than the zero value of the soldiers rendered powerless by the presence of game piece 22 in the same section therewith. On the other hand, Dictatorship can neutralize the influence of game piece 22 by placing game piece 26 into the section occupied by game piece 22, game piece 26 symbolizing "Censorship" which overcomes the effect of the "Appeal to freedom," since the soldiers previously subjected to the effect of the

"Appeal to freedom" no longer listen to said appeal. Consequently said soldiers regain their value and can capture any inferior forces of the opponent and also regain their freedom of movement.

Game pieces 24 and 28 corresponding respectively to subversive activities of the Dictatorship and to the counteractivities of the Democracies are, like opposing game pieces 22 and 26, useful for exerting influence on the enemy soldiers, but not on the President or on the Dictator or other rulers of the enemy countries, respectively, but as in the case of game pieces 22 and 26, game pieces 24 and 28 cannot capture any enemy soldiers or ruler.

As hereinbefore stated, chance members, preferably dice, are used for determining which game pieces can be moved by the player having the next move. As here shown each player has a set of chance members or dice. The dictator's chance members or dice are illustrated in Figs. 13 to 15 and are indicated generally by the reference numerals 30 and 32 and the chance members or dice of the Democracy are illustrated in Figs. 10 to 12 and are designated by the reference numerals 34 and 36. The faces of dice 30 and 32 of the Dictatorship are marked as illustrated in Figs. 14 and 15, respectively, and the faces of the dice 34 and 36 of Democracy are marked as indicated in Figs. 11 and 12, respectively. Thus, when it is the Dictator's turn to play he throws dice 30 and 32 and the marks which appear on the top faces of the dice thus thrown determine which game pieces he can move and as stated above, said game pieces can move only from one section, starting with section I (Agriculture) at the start of the game, to any adjacent section. It will be observed that one of the dice, namely die 32, of the Dictatorship has one surface thereof marked with the legend "Dictator III." If this legend appears on the top surface of the die when the dice are thrown by the player representing Dictatorship, said player cannot make any move but must await his next turn. The Dictator being the aggressor makes the first move and therefore starts the game. The game pieces which Democracy can then move likewise depends upon the throw of the dice, the indications on the top faces thereof determining the game pieces which the player representing Democracy can move, the movement at the start of the game being from section I of the Democratic country to any adjacent section. It will be observed that die 36 of the player representing Democracy carries on one face thereof the legend "Strikes and profiteering," and it will be understood that if said legend is shown on the top surface of the said die 36 when the dice are thrown, the player representing Democracy cannot make any move and must await his next turn to throw the dice. It will be noted that the dice of each player carry legends corresponding to the game pieces which he can move and that a plurality of the faces of each die are marked with the legend "Soldier" since each player has a plurality of soldiers. If one player moves a soldier or ruler into section I of the enemy country, the original value of the game piece representing said soldier or ruler, as the case may be, is doubled. For example, a soldier placed in section I of the enemy country has the value 2 instead of 1, the President has the value 8 instead of 4, and the Dictator has the value 10 instead of 5. This increased value of the game piece is main-

tained, however, only so long as the game piece remains in section I of the enemy, and assumes its original value as soon as it is moved from said section of the enemy country.

If one player moves the game piece corresponding to a soldier or to the ruler of the country into section II (Industry), of the enemy country, the industrial output and the military activity of that country is disturbed or reduced. Consequently in order that the game may be influenced by this factor, the player of the country whose industrial section is thus occupied can move only one of the game pieces indicated by the throw of dice, said player having the choice of determining which game piece he may move.

While the Dictatorship has greater numerical value, indicative of more power than the Democracy, the morale of the Dictatorship is more easily impaired. This factor is brought into the game of the present invention by allowing the player representing Democracy to continue his moves so long as his preceding move resulted in a victory for Democracy. Accordingly whenever Democracy can strike a blow against Dictatorship, the soldiers of Dictatorship lose confidence, while on the other hand, the soldiers of Democracy gain confidence after a victorious battle and are spurred to renewed activity symbolized by the allowance to the Democracy of an additional throw of the dice and a move pursuant thereto whenever Democracy captures any of the game pieces of the Dictatorship. The superiority in the morale of the Democracy also is further introduced as a factor in the game by reason of the important fact that the player representing the Dictatorship loses the game if either (1) the Dictator is captured or (2) if all of the Dictatorship's soldiers are captured, whereas Democracy can lose only if both its President or ruler and all the soldiers of Democracy are captured.

As described above, the game is played by two players, but the same game can be played by more than two players; for example, three or four players, in which case a game board 40, illustrated in Fig. 16, is used. Said game board has parts 42 and 42A representing allied countries constituting one side of the conflict, and parts 44 and 44A representing allied countries and constituting the other side of the conflict, each of said countries having sections corresponding to sections of the countries on game board 40, described above. When four players participate in the game, two of the players constitute one side as a partnership and the other two players constitute the other side as a partnership, for example, the allied Democracies on the one hand, and the allied Dictatorships on the other. Each player can move only his own game pieces, but can consult with his partner, but the value of the game pieces of the player of one side are added to the value of the game pieces of the player on the other side. For example, if one player representing a Democracy has three soldiers and his allied player has two soldiers in the same section in which the total number of soldiers of the Dictatorship countries in said section is less than five, the soldiers of the allied Democracies in said section capture the Dictatorships' soldiers which are in the same section. Game board 40 also has a section VIII which may represent a neutral or non-belligerant country which cannot be invaded by either of the warring countries. Section VIII, however, may be omitted or can be used otherwise than as

above stated, as determined by the players for introducing variations into the game.

When the game is played by three players, board 40 is also used, and preferably two players represent two separate Dictatorships and one player represents one Democracy, each player being the enemy of each of the other players. Each player can capture the game pieces of any other player in the same section provided, of course, that his strength is numerically superior in value to that of either of his opponents, it being unnecessary for this purpose that his numerical strength be greater than the combined numerical strength of both opponents in the same section. It will be noted also that the subversive or "Fifth column activities" of one Dictatorship is effective against the other Dictatorship so that the two enemy Dictatorships can use their subversive activities against each other.

Thus it is seen that the game apparatus disclosed herein is well adapted to accomplish the several objects of the invention. It will be understood, however, that while I have disclosed the preferred embodiment of the invention, the latter may be embodied otherwise than as here shown and that in the illustrated embodiment certain changes may be made. Therefore, I do not wish to be limited to the embodiment or forms of the invention herein disclosed, except to the extent which may be required by the scope of the appended claims.

Having thus described my invention, what I claim and desire to secure by Letters Patent is:

1. In game apparatus of the character described, a game board having a territorial border line on its upper surface and surface sections at opposite sides of said border line designating areas or activities of enemy countries, respectively, game pieces corresponding to soldiers of each of said countries subject to capture by soldiers in greater force of the enemy when the soldiers of the two countries are in the same section of either country, and game pieces bearing on their faces indicia of abstract forces which are capable of rendering enemy soldiers powerless or of reduced power when one of said last mentioned game pieces is in the same section with one or more enemy soldiers.
2. In game apparatus of the character described, a game board having a territorial border line on its upper surface and surface sections at opposite sides of said border line designating areas or activities of the enemy countries, respectively, game pieces corresponding to soldiers of each of said countries subject to capture by soldiers in greater force of the enemy when the soldiers of the two countries are in the same section of either country, game pieces bearing on their faces abstract forces which are capable of rendering enemy soldiers powerless or of reduced power when one of said last mentioned game pieces is in the same section with one or more enemy soldiers, and separate chance members for each country, respectively, having indicia thereon of said abstract forces and operable during the playing of the game for indicating which of said game pieces of the corresponding countries, respectively, are movable against the enemy country during the progress of the game.
3. In game apparatus of the character described, a game board having a territorial border line on its upper surface and surface sections at opposite sides of said border line designating areas or activities of enemy countries, respectively, game pieces corresponding to soldiers of

each of said countries subject to capture by soldiers in greater force of the enemy when the soldiers of the two countries are in the same section of either country, and game pieces having indicia thereon corresponding to opposing principles of Democracy and Dictatorship, respectively, which are capable of rendering enemy soldiers powerless or of reduced power when one of said last mentioned game pieces is in the same section with one or more enemy soldiers.

4. In game apparatus of the character described, a game board having a territorial border line on its upper surface and surface sections at opposite sides of said border line designating areas or activities of enemy countries, respectively, game pieces corresponding to soldiers of each of said countries subject to capture by soldiers in greater force of the enemy when the soldiers of the two countries are in the same section of either country, game pieces having indicia thereon corresponding to opposing principles of Democracy and Dictatorship, respectively, which are capable of rendering enemy soldiers powerless or of reduced power when one of said last mentioned game pieces is in the same section with one or more enemy soldiers, and separate chance members for each country having indicia thereon of said principles for indicating which of said game pieces of the corresponding countries, respectively, are movable against the enemy country during the progress of the game.

5. In game apparatus of the character described, a game board having a territorial border line on its upper surface and surface sections at opposite sides of said border line designating areas or activities of enemy countries, respectively, game pieces corresponding to soldiers of each of said countries subject to capture by soldiers in greater force of the enemy when the soldiers of the two countries are in the same section of either country, game pieces having indicia thereon corresponding to subversive activities and imprisonment therefor, respectively, and separate chance members for each country having indicia thereon for indicating which of said game pieces of the corresponding countries, respectively, are movable against the enemy country during the progress of the game.

6. In game apparatus of the character described, a game board having a territorial border line on its upper surface and surface sections at opposite sides of said border line designating areas or activities of enemy countries, respectively, game pieces corresponding to soldiers of each of said countries subject to capture by soldiers in greater force of the enemy when the soldiers of the two countries are in the same section of either country, game pieces having indicia thereon corresponding to censorship and freedom of speech, respectively, and separate chance members for each country having indicia thereon for indicating which of said game pieces of the corresponding countries, respectively, are movable against the enemy country during the progress of the game.

7. In game apparatus of the character described, for use with a game board having a territorial border line on its upper surface and surface sections at opposite sides of said border line designating areas or activities of enemy countries, respectively, game pieces corresponding to soldiers of each of said countries subject to capture by soldiers in greater force of the enemy when the soldiers of the two countries are

in the same section of either country, game pieces corresponding to abstract forces which are capable of rendering enemy soldiers powerless or of reduced power when one of said last mentioned game pieces is in the same section with one or more enemy soldiers, and separate chance members for each country, respectively, indicating which of said game pieces of the corresponding countries, respectively, are movable during the progress of the game, said chance members of each player comprising dice having the faces thereof marked with legends denoting said game pieces, respectively.

8. In game apparatus of the character described, for use with a game board having a territorial border line on its upper surface and surface sections at opposite sides of said border line designating areas or activities of enemy countries, respectively, game pieces corresponding to soldiers of each of said countries subject to capture by soldiers in greater force of the enemy when the soldiers of the two countries are in the same section of either country, game pieces corresponding to abstract forces which are capable of rendering enemy soldiers powerless or of reduced power when one of said last mentioned game pieces is in the same section with one or more enemy soldiers, and separate chance members for each country, respectively, indicating which of said game pieces of the corresponding countries, respectively, are movable during the progress of the game, said chance members of each player comprising dice each having a plurality of its faces marked with a legend denoting a soldier game piece and at least one of said game pieces of each player carrying legends denoting said other game pieces of said player.

9. In game apparatus of the character described, a plurality of sets of opposing game pieces to be utilized by opposing players, respectively, in playing the game, each of said sets including pieces having indicia thereon of abstract forces, the abstract forces denoted by the indicia of said last mentioned game pieces of one of said sets being opposed to the abstract forces denoted by the indicia of said last mentioned game pieces of another of said sets, and other game pieces in each of said sets having indicia thereon of said abstract forces, respectively, of the same set and operable by the manipulation thereof during the playing of the game to determine whether any and if so which of said forces can be utilized by the player of the corresponding set of game pieces.

10. In game apparatus of the character described, a plurality of sets of opposing game pieces to be utilized by opposing players, respectively, in playing the game, each of said sets including pieces corresponding to strictly military forces and including also other pieces having indicia thereon of abstract forces, the abstract forces denoted by the indicia of said last mentioned game pieces of one of said sets being opposed to the abstract forces denoted by the indicia of said last mentioned game pieces of another of said sets, and at least one die included in each of said sets of game pieces having on different faces, respectively, thereof indicia of said military and abstract forces, the abstract force denoted on the die of one of said sets being opposed to the abstract force denoted on the die of another of said sets.

F. DOUGLAS WILLIAMS.
